Attorney

UNITED STATES PATENT OFFICE.

ELIZABETH H. MARSHALL, OF MARKHAM, VIRGINIA.

FEED-BAG HOLDER.

No. 881,813.

Specification of Letters Patent. Patented March 10, 1908.

Application filed May 29, 1907. Serial No. 376,292.

To all whom it may concern:

Be it known that I, ELIZABETH H. MARSHALL, a citizen of the United States, residing at Markham, in the county of Fauquier 5 and State of Virginia, have invented new and useful Improvements in Feed-Bag Holders, of which the following is a specification.

This invention relates to improvements in 10 feed bag holders, and particularly to improvements in devices of that kind designed for supporting a nose bag from the neck of the animal, the object of the invention being to provide a simple, cheap and effective 15 holder adapted to be supported from the collar of the harness or neck of the animal and to securely hold the bag in position, and which is designed to be folded in close compass for storage or transportation, thereby 20 enabling it to be conveniently carried.

In the accompanying drawing illustrating 25 the invention, Figure 1 is a perspective view showing the application of the invention. Fig. 2 is a similar view of the device detached, showing one of the coupling sleeves in section.

The device is preferably made largely or 30 entirely of wire of proper gage to afford the requisite strength and galvanized or otherwise treated to prevent rust, and comprises a supporting member 1 in the form of a yoke 35 adapted to rest upon and be supported from the collar of the harness or neck of the animal. The yoke may engage the collar in rear of the 40 hames, and may be applied and removed without the necessity of detaching the hames or any of the parts of the harness.

The lower ends of the sides or arms of the yoke are bent upwardly to provide uprights 40 or standards 2 formed at their upper ends with spring coils 3 and forwardly projecting extensions 4 arranged horizontally in advance of the coils. Pivots connected with said extensions 4 are forwardly extending 45 bag supporting arms 5 adapted to extend forwardly on opposite sides of the neck of the animal and provided at their forward ends with hooks 6 to engage eyes 7 on the opposite sides of the nose bag 8, by which the latter may be detachably applied thereto and supported in operative position.

The rear ends of the arms 5 and the extensions 4 project through coupling sleeves 9 and are provided at their points of junction with eyes 10 for the passage of pivot pins or pintles 11. These pins serve to de-

tachably connect the extensions 4 with the sleeves 9 and form pivotal supports for the arms 5, which are held from downward movement below a substantially horizontal position by their bearing upon the lower forward portions of the sleeve. The upper front surfaces of the sleeve are provided with slots 12, adapting the arms 5 to be swung from a horizontal to a vertical position and vice versa. By this means the arms may be swung upward to a vertical position substantially parallel with the yoke 1 to fold the device for storage or transportation, and may be turned down to a horizontal position for use, as illustrated in Figs. 1 and 2.

From the foregoing description, taken in connection with the drawing, the construction and mode of operation of the device will be readily understood, and it will be seen that the invention provides a simple, inexpensive and efficient type of holder which may be conveniently applied and removed and conveniently folded for storage or transportation and unfolded for use.

It will be understood that the spring coils 3 permit the arms 5 to yield downward to a slight extent under the weight of the bag, and, as the bag grows lighter, move the arms gradually upward to elevate the bag on the nose of the animal, allowing the latter to reach entirely down to the bottom of the bag to consume the food therein. As a result, scattering and waste of grain will be effectively prevented.

Having thus fully described the invention, what is claimed as new is:

1. A device of the character described comprising a yoke, bag supporting arms pivotally connected with the yoke, and slotted coupling sleeves carried by the yoke and adapted to support said arms when in operative position.

2. A device of the character described comprising a yoke having upturned standards at its lower end provided with forward extensions, arms pivoted to said extensions, and a supporting connection between the arms and extensions adapted to permit the arms to fold in the direction of the yoke.

3. A device of the character described comprising a yoke having forward extensions, supporting arms, sleeves engaging the extensions and arms, fastening devices connecting the sleeves with the aforesaid parts and pivoting the arms for vertical movement toward and from the yoke, said sleeves being

provided with slots for the movement of the arms.

4. A device of the character described comprising a yoke bent at its lower end to provide upwardly extending standards having forward projections, coupling sleeves engaging said projections and having their upper front portions slotted, and arms pivoted

within said sleeves and movable through said slotted portions.

In testimony whereof, I affix my signature in presence of two witnesses.

ELIZABETH H. MARSHALL.
